UNITED STATES PATENT OFFICE.

ALFRED J. KIECKHEFER, OF MILWAUKEE, WISCONSIN, ASSIGNOR TO NATIONAL ENAMELING & STAMPING CO., INC., OF MILWAUKEE, WISCONSIN, A CORPORATION OF NEW JERSEY.

OIL-STOVE BURNER-ADJUSTING MEANS.

Application filed October 12, 1921. Serial No. 507,259.

To all whom it may concern:

Be it known that I, ALFRED J. KIECKHEFER, a citizen of the United States, and resident of Milwaukee, in the county of Milwaukee and State of Wisconsin, have invented certain new and useful Improvements in Oil-Stove Burner-Adjusting Means; and I do hereby declare that the following is a full, clear, and exact description thereof.

10 My invention relates to a new and useful improvement in connection with the means for adjusting oil-stove burners whereby the burner is adjusted to its proper level with reference to the oil reservoir.

15 The object of the invention is generally to simplify and otherwise improve this adjusting means so as to make it more positive in its operation and less likely to get out of order as well as to reduce the cost of manufacturing the same.

A more specific object of the invention is to manufacture in one piece the lifting member by which the height of the burner is regulated.

25 A further object of the invention is to provide improved means for attaching the handle whereby the structure is simplified as well as made more secure.

A still further object of the invention is 30 to provide improved means by which the normal position of the entire mechanism of the burner and regulating means can be bodily adjusted and securely held in the desired position in accordance with the level 35 of the oil feed and the conditions under which the burner is to be used.

In describing my invention reference will be made to the accompanying drawings, in which:—

40 Figure 1 is a view in side elevation of my invention with parts thereof shown in section.

Figure 2 is a detail sectional view taken on the line 2—2 of Figure 1.

45 Figure 3 is a rear elevation of the burner regulating means.

Figure 4 is a sectional detail view on the line 4—4 of Figure 1.

50 Figure 5 is a perspective view of the bracket for supporting the regulating means.

Referring more specifically to the drawings the numeral 1 indicates a fuel feed pipe having the extensible portion 2 which is connected with the burner 3, the latter being

vertically adjusted to regulate the flame 55 through the medium of a link 4. A bracket 5 is provided for supporting the means for regulating the burner and has a vertical portion 7 which is secured to the feed pipe which extends through an orifice 6 in the horizontal portion of the bracket. The bracket is also extended laterally as shown at 8 and provided with a hole 9 in which the drum lifting rod 10 is guided. A trunnion 11 is mounted horizontally in the bracket 5 and the lifting member 12 is journaled thereon and provided at one end with an offset portion 13 connected with the lower end of the link 4 and at its other end with an offset portion 14 to which the handle 16 is attached. The handle as will be noted is formed with a longitudinal groove 15 which fits snugly over the offset portion 14 and is securely held thereon without allowing any play. A portion of the handle is also extended to form a pointer 17 which in connection with the usual dial plate 18 indicates the position to which it is designed to be adjusted.

In constructing the lifting member 12 in 80 one piece from strap metal or the like the cost of production is reduced to a minimum and the relative position of the handle and pointer is positively determined with respect to the position of the burner. There is no 85 chance for any connections to become loose or for anything to get out of order.

In order that the entire mechanism of the burner and lifting means may be bodily adjusted so that the range of regulation of the 90 burner by means of the handle 16 may be properly determined I have provided a clip 19 which is somewhat resilient. This clip fits around the upstanding portion 1 of the feed pipe and its extremities 20 extend in 95 diverging relation to the vertical portion 7 of the bracket. These extremities are provided with openings through which are inserted the attaching screws 21. The entire mechanism is therefore supported by the 100 feed pipe and may be readily adjusted thereon to the point desired. The peculiar shape of the attaching clip 19 results in a secure grip being obtained upon the pipe, when the screws are drawn tight. In other words 105 when the extremities 20 are drawn toward the plate 7 the diverging relation of these extremities will cause the same to be drawn

inwardly toward the pipe and securely grip the same. Ribs or shoulders 22 are also formed in the vertical portion 7 of the bracket which add strength to the bracket in 5 resisting the force of the clamping action and serve also as abutments to prevent the nut from becoming loose.

I claim as my invention:—

- 10 1. In a device of the character described, a frame, a burner vertically slidable thereon, a pivot bolt supported horizontally in the frame below the burner, a metallic strap extending parallel to said bolt and having integrally formed lateral extensions at each 15 end which have a pivotal bearing on said bolt, one of said extensions being connected beyond its bearing with said link, and a handle having a longitudinal channel in which the projecting end of the other integral extension is secured.
- 20 2. In a device of the character described, an oil burner, a pipe having a vertical portion for supplying oil thereto, a frame in which said burner is adjustably supported, 25 said frame having an opening in which the vertical portion of the pipe is fitted and a vertical attaching portion, said attaching portion having means for adjustably clamping it to the pipe including a spring clip having a central portion extending around 30 the pipe and a tongue at each end extending in a diverging relation to the attaching

portion of the frame and clamping bolts extending through said tongues and attaching portion whereby the tightening of said bolts 35 will draw the ends of the clip inwardly to tighten its grip on the pipe.

3. In a device of the character described, an oil burner, a vertical substantially stationary pipe, a second pipe connecting said burner and stationary pipe and slidably related to said stationary pipe, means for adjusting the height of said burner relatively to said stationary pipe, a support for said means having a face in contact with said stationary pipe, a spring clip curved to contact with said pipe throughout its curved portion and having a pair of arms extending outwardly from said curved portion, and attaching means for drawing said arms toward 50 said support, said arms when free from stress extending outwardly at an angle to the normal to the surface of said clip at the point where they join such surface, and adapted to be drawn into approximate coincidence with said normal to thereby cause the portion of the clip at the inner end of said arms to bite into said stationary pipe.

In testimony that I claim the foregoing I have hereunto set my hand at Milwaukee, in 60 the county of Milwaukee and State of Wisconsin.

ALFRED J. KIECKHEFER.
